ELECTRIC STOP MOTION FOR KNITTING MACHINES

Ben Wachsmann, Brooklyn, N. Y., assignor to
Wachsmann Sons', Inc., a corporation of New
York

Application April 6, 1940, Serial No. 328,250

1 Claim. (Cl. 66—163)

This invention relates to electric stop motions for knitting machines. Such devices, which are controlled by the travelling yarn, may be classified into end detectors and knot detectors. The end detectors are arranged to operate to close an electric circuit when the yarn breaks or runs out. The knot detectors operate to close the circuit when a knot or other obstruction occurs in the yarn.

The object of this invention is to provide a combined end detector and knot detector into a single device which may be used in place of the two separate devices or which may be used indiscriminately as an end detector or as a knot detector. In the accompanying drawing illustrating the invention

Fig. 1 is a side view of the device.

Fig. 2 is a face view looking from the left in Fig. 1.

Fig. 3 is a plan view.

Fig. 4 is a detail view of a modified member to be used in the device.

Those who are familiar with the art of knitting machines know that stop motions are mounted in a suitable position in the machine in the path of the travelling yarn. They are also entirely familiar with the operations and functions of such devices so no extended description as to these features are necessary in this specification. Now referring to the drawing the stop motion device is mounted upon a bar 5 which represents any suitable member of a knitting machine. The bar carries a screw or bolt 6 with a knurled or other nut 21. Upon the bolt is supported a rotatable disk 7 which has porcelain eyelets 8, 9 of graduated sizes. Upon the bolt 6 is also placed a bracket 9 which carries a contact box 10. The upper end of the bracket is provided with a porcelain eyelet 11 of the same size as the largest eyelet 8. A detector lever 12 is pivoted at 13 in the box 10. The lever has a yarn engaging eye or loop 14 adapted to enclose and rest against the yarn 15 above the eyelet 11. Inside the box the lever 12 has a contact heel 16. When the yarn breaks or runs out or when a slack occurs in the yarn the lever 12 falls forward by gravity and its contact heel then contacts a spring terminal 17 inside the box to close an electric circuit, said inside terminal being connected at 18 to an outside terminal 19 through insulation 20. Spacing washers 23 and 29 are provided to permit free rotation of the disk 7.

In operation the device is mounted upon the bar 5 and nut 21 screwed down sufficiently so that the device is held on the bar. Then the disk 7 is rotated so as to bring a particular eyelet 8 into alignment with the eyelet 11 so that the yarn 15 can be passed straight upwards through such eyelets as shown, the nut 21 being loosened sufficiently to permit such rotation. Then the nut 21 is

tightened to hold the disk in such selected position. The eyelet 8 selected for alignment is chosen with relation to the yarn. If the yarn is very fine, a very small eyelet 8 is brought into operating position. For thicker yarns or maybe for yarns being flossier a correspondingly larger eyelet 8 is selected. For each yarn the selected eyelet 8 is such that when a knot occurs upon the yarn, it cannot pass upwards through the selected eyelet.

The operation is therefore this. When the yarn breaks or runs out the detector will fall forward and close the circuit. If a knot occurs on the yarn it cannot pass upwards through the selected eyelet 8 in the disk 7. The yarn therefore cannot travel through the device or machine. The yarn breaks and the detector lever is again operated.

In place of the disk 7 an arm 25 such as shown in Fig. 4 may be used. The arm has a hole 26 which fits over the bolt 6. It also carries two different sized porcelain eyelets 27 and 28. By substituting the arm 25 for the disk 7 the device becomes somewhat simpler and more inexpensive.

It will be understood that in this case the arm is moved slightly on the bolt 6 in order to bring the selected eyelets 27 or 28 into alignment with the said eyelet 11. Several arms having combined a complete series of graduated eyelets may be provided for a single knitting machine for ready selection of the proper eyelet.

The device is inexpensive, easy to install and operate and serves as a combined end detector and knot detector depending upon the kind of yarn used and adjustment of the device.

I claim:

In a combined end detector and knot detector for knitting machines, a unitary article of manufacture comprising a supporting bracket including a horizontal arm and an upright arm, a fixed yarn guiding eyelet in the upright arm, a disk rotatably supported on the horizontal arm below the same a distance below said fixed eyelet, a plurality of yarn guiding eyelets of different sizes mounted in said disk, said disk being adapted to selectively move any one of the eyelets therein into yarn guiding alignment with said fixed eyelet, a bolt in said bracket for rotatably supporting the said disk thereon and for mounting said bracket on a knitting machine, a nut on said bolt for securing said disk after the eyelets therein have been aligned as aforesaid and for securing the bolt to the knitting machine, a contact box on said horizontal bracket arm and a gravity actuated lever pivoted on said box to close an electric circuit therein, said lever extending forwardly of said bracket into engagement with a yarn passing through the aligned eyelets.

BEN WACHSMAN.
